UNITED STATES PATENT OFFICE.

WILLIAM BURR GREGG, OF HACKENSACK, NEW JERSEY, ASSIGNOR TO THE GREGG COMPANY, LIMITED, OF HACKENSACK, NEW JERSEY, A CORPORATION OF NEW YORK.

CAR-DOOR FASTENING.

1,308,779.

Specification of Letters Patent.

Patented July 8, 1919.

Application filed August 28, 1917. Serial No. 188,596.

To all whom it may concern:

Be it known that I, WILLIAM BURR GREGG, a citizen of the United States, residing at Hackensack, in the county of Bergen and

5 State of New Jersey, have invented certain new and useful Improvements in Car-Door Fastenings; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15

My invention relates to car door fastenings. It has for its object to provide a fastening which will lock or fasten the door at opposite points or positions when closed, 20 and capable of being released or fastened at one point when released or fastened at the other point; also which will be strong and efficient and may be made and applied at relatively small cost. To the accomplishment 25 of the foregoing and such other objects as may hereinafter appear the invention consists in the features hereinafter particularly described and then sought to be clearly defined by the claims, reference being had to the accompanying drawings forming a part hereof and in which—

Figure 1 is a view, in perspective, of a portion of a car with the invention applied thereto;

35 Fig. 2 is a vertical central section through Fig. 1; showing in dotted lines the locking lever in unlocking position;

Fig. 3 is a sectional view, enlarged scale, of the upper part of the fastening.

40 In the drawing the numeral 1 designates a car body of any approved type of construction, and 2 a door thereto. This door, single or double, is swingingly connected by suitable hinges 3 to an upright 4 and pref- 45 erably comprises a metallic frame 5 with

wooden filler timbers 6, and at the corners is strengthened by gussets 7 and 8 prefer- 50 ably triangular in form or shape as illus- trated, the gussets 7 at the free end of the door projecting beyond the door frame so as to form flanges 9 which will overlay the adjacent edge of the companion door if a double door be employed, or the side of the door frame if only a single door be used.

55 The fastening consists of a hook shaped

latch 10 adapted, when the door is closed, to engage say the inner side or edge of the top member 10^a of the car frame, which may be a metal channel bar or iron, so as to securely fasten the door at that point. 60 This latch is preferably formed as a part of an arm or lever 11 and is pivoted say by a pivot pin 12 to a suitable part of the door preferably in a housing 13 secured by bolts or otherwise to the metallic frame of 65 the door. This lever extends the length of the door so that its outer end may be secured by a suitable fastening or lock to the car frame, say, to the bottom sill 14. The fastening for this end of the lever may be 70 any suitable fastening but preferably consists of a pocket 15 having a swinging latch 16 which when swung across the lower end of the lever and dropped into the recess provided for it will securely hold that end of 75 the lever to the car. This provides an efficient fastening for the door at opposite points of the door opening and enables one fastening or latch to be thrown into or out of holding position as the other is thrown 80 into or out of holding position. The arm or lever which constitutes a part of the door holding means extends across the door from one fastening to the other and thus serves also to increase the efficiency of the locking 85 or fastening means as well as contributing toward strengthening or bracing the door. The pivot of the latch and lever is preferably positioned, as shown, so that when the lower end of the lever is released and the 90 door pressed outwardly the upper latch will disengage from the top member with which it interlocks when the door is closed and thus permit the door to swing open. While it is preferred to so dispose the pivot pin 95 that the automatic disengagement mentioned will take place yet it may be otherwise disposed so that manual operation of the lever will be necessary to disengage the latch from holding position without departing from essential features of the invention. 100

When the door is closed the flanges 9 of the gussets 7 will lap over the edge of the companion door, if a double door be used, and the fastening described will serve to 105 hold both doors in their closed position, or if only a single door be used these flanges will lap over the edge of the door frame opening.

The fastening has been illustrated and de- 110

scribed as applied to a vertically swung door but it is obvious that it may be applied to a horizontally swung door; or in other words, the invention is the same whether 5 applied to a door hinged so as to swing on a vertically disposed axis or hinged to swing on a horizontally disposed axis.

The preferred position for the latch and lever is that illustrated but it may be otherwise placed, and one or more be employed as 10 found desirable or necessary to meet conditions.

Having described the invention, and set forth its merits, what is claimed is:

15 1. In a car door fastening, a lever pivotally mounted at only one end to the door to swing away from the door and provided at that end with a latch disposed to interlock with a part of the car structure, said lever being extended across the door, and means provided for fastening the lever at the end opposite that at which the interlocking latch is provided.

20 2. In a car door fastening, a lever provided at one end with a latch adapted to

interlock with a part of the car structure and pivotally mounted so that pressure on the door will disengage the latch, said lever being extended across the door, and means provided for fastening the lever at the end 30 opposite that at which the interlocking latch is provided.

3. In a car door, gussets applied to the door so as to project beyond the edge of the door and overlap the edge of an adjacent member, and a lever pivotally mounted at one end on the door so as to swing outwardly from the door and at that end formed with a latch to interlock with a part of the car structure, said lever being extended across 35 the door, and means provided for fastening the lever at the end opposite that at which the interlocking latch is provided.

In testimony whereof I affix my signature in presence of two witnesses.

WILLIAM BURR GREGG.
